LOWER PLUG FOR CEMENTING WELLS

Zeb A. Dyer, Los Angeles, Calif., assignor of
one-fourth to Charles Lamb and one-fourth
to Douglas R. Radford, both of South Pas-
adena, Calif.

Application October 12, 1938, Serial No. 234,625

5 Claims. (Cl. 166—1)

This invention is an improvement in a lower cementing plug for use primarily in the cementing off operations in oil wells.

In cementing off operations in wells, a charge 5 of liquid cement is forced down the casing to the bottom of the hole and ejected into the area surrounding the lower end of the well casing. Most operators prefer to isolate the cement charge during its introduction to the point of use by 10 cementing plugs below and above the charge which protect the cement from being intermingled with mud and water and also furnish a piston like object by which rotary mud under pressure is used to force the plugs and cement 15 through the casing to the point of use.

This application is a continuation in part of my co-pending application filed December 22, 1937, Serial Number 181,133. In that application I illustrate a lower cementing plug comprising 20 a body member having enlarged fluted end portions, a reduced middle portion, and an annular flexible wiper or washer extending outwardly from the reduced portion. The body is of integral construction and the annular rubber 25 washer is stretched thereon.

An object of my present invention is to construct a plug of the same general type shown in the previous application of two parts to facilitate the casting of same as well as making it possible 30 to install the rubber washer more easily and with a more positive seal with the body member.

Another object of the invention is to provide a plug of the same general design utilizing only a half of the body member, thus reducing cost.

A further object is to construct a plug with a novel T form of annular washer to improve the seal of same with the body of the plug for preventing leakage where the washer fits into the plug body.

In the drawing:

Figure 1 represents a cross section of the lower extremity of the point of drilling in an oil well with my novel plug therein.

Figure 2 is a similar view showing the plug 45 resting upon a float valve at the bottom of the well, and the cementing operation in progress.

Figure 3 is a top view of my plug.

Figure 4 is a section of the plug taken on the line 4—4 of Figure 3.

Figure 5 is a similar section of a modified form of plug utilizing a half of the plug shown in Figure 4.

Figure 6 is a section similar to Figure 4 showing a modified form of washer having a T cross 55 section.

The cementing plug 10 illustrated in Figures 3 and 4 is constructed of a lower part or section 11 and an upper part or section 12. These parts are externally identical, and differ internally in the following particulars:

The upper part has a threaded extension 13 adapted to screw into a threaded recess 14 in the lower part for coupling the two parts together. Instead of being threaded, the extension 13 and recess 14 may be formed in any suitable way to 10 be united by friction, as by providing annular corrugations instead of threads, or the extension and recess may have unbroken walls if the parts are constructed of material having adequate surface tenacity. The lower part has an annular 15 shoulder 15 at the upper end which cooperates with lower face 16 of the upper part to form an annular recess 17 for receiving annular rubber washer 18.

This washer 18 has an external diameter 20 slightly greater than the external diameter of the parts 11 and 12. It is preferably of sufficient thickness to result in some compression of same when the parts 11 and 12 are brought together.

Externally, the complete plug comprises a 25 roughly cylindrical body with a reduced middle portion 20 frusto-conical in design, and with longitudinal fluid passages 21 communicating with the reduced portion 20 and continuing radially to communicate with a central fluid cavity 30 22 at each end. A castellated form results in which there are ample longitudinal fluid passages, and seating means 25 in the form of legs or base 26 which occupy only a fraction of the area defined by the cylindrical cross section of 35 its plug. This construction affords a free flow of fluid past the plug at the proper time. Inasmuch as both ends are alike, the plug is reversible that is, may be inserted in the well casing either end up.

In Figure 1 the plug is descending in the well casing 30 below a charge of liquid cement 31. The plug body fits loosely in the casing, acting principally as a weighted guide for the washer 18 which has a snug fit against the walls of the 45 casing and seals off the cement from mud or water below. At the top of the charge of cement is a top plug 35, see Figure 2, of suitable design and construction to function as a piston. The top plug is forced downwardly by rotary mud 36 50 under pressure, pushing the cement before it.

When the assembly of top plug, cement and lower plug reaches the bottom of the well hole, the lower plug engages a float valve or other casing terminal 37 and comes to rest thereon. 55

Continued pressure from above causes the outer edges of the washer 18 to collapse downwardly, permitting the liquid cement to pass through the fluid passage of the lower plug and through the 5 float valve 31. As the cement is forced below the end 38 of the casing it fills the cavity 39 at the lower end of the well hole and passes upward into the area 40 surrounding the casing.

After the cement has hardened, the cementing 10 plugs are drilled out to clear the casing.

The modified form of plug illustrated in Figure 5 comprises a lower part 11 identical to the lower part in Figure 4, and a similar washer 18. These are assembled by a cap having a threaded extension 51 similar to extension 13 of Figure 4. As an alternative mode of construction part 11 and cap 50 may be molded or formed as a single piece with the annular recess therein, and the washer stretched over and allowed to snap 20 into place. I also consider it to be an equivalent to use the part 11 without cap 50, and vulcanizing or otherwise securing washer 18 to the top of the part 11.

This plug must be inserted in the well in the 25 position shown in Figure 5. It performs the same function as the double ended plug and may be used singly, or in tandem, the base 26 of one plug seating on the upper flat surface 52 of another plug.

30 In the plug shown in Figure 6 the washer 18a is formed with a T cross section which provides an annular flange 70 extending downwardly and upwardly from the annular flat portion 71 of the washer. Lower and upper parts 11a and 35 12a are formed with annular recesses 72 and 73 respectively which receive the flange 70. This junction between the washer and the plug body improves the seal between washer and plug body and eliminates any possibility of leakage past 40 the inner edge of the washer which otherwise might occur by distortion of the washer when under pressure.

This T form of washer may be used with the 45 plug illustrated in Figure 5. In such case, the lower part should have the recess as found in part 11a, and the cap should have a recess to correspond with the recess in part 12a.

What I claim is:

1. A cementing plug of the type described comprising a pair of cooperating members secured together and forming an approximately cylindrical body having longitudinal fluid passages, 5 and an annular flexible washer seated between the members and having a diameter greater than the diameter of the body, the washer being formed with a flange at the inner edge thereof and the said members being formed with annular 10 recesses to receive the flange.

2. A cementing plug of the type described comprising a guide member made in two parts having complementary annular recesses, and a flexible washer secured to the guide member with a flange 15 fitting in the annular recesses.

3. A cementing plug of the type described comprising two members forming an approximately cylindrical body having a central end fluid cavity and longitudinal fluid passages communicating 20 therewith, and an annular flexible washer seated between the members and having an external diameter greater than the diameter of the body, the washer being formed with a flange at the inner edge thereof and the said members being 25 formed with annular recesses to receive the flange.

4. A cementing plug of the type described comprising a member formed in two parts having enlarged fluted end portions and a reduced middle portion, there being aligned annular longitudinal recesses at the inner ends of the two parts, and a flexible washer seated between the members and having a T flange fitting in the recesses, the 30 washer having an external diameter greater than 35 the diameter of the member.

5. A cementing plug of the type described comprising a guide member having an enlarged castellated end and a reduced portion and an annular longitudinal recess in the reduced portion, a flexible washer seated in the reduced portion and having a flange fitting in the recess and having an external diameter greater than the diameter of the castellated end, and readily detachable means securing the washer on the guide 40 member.

ZEB A. DYER.
